Fig. 3

Fig. 6

Fig. 5

Fig. 4

Fig. 7

FIG. 1 is a top perspective view of a molded guitar carrying case shell, showing our new design;

FIG. 2 is a bottom perspective view;

FIG. 3 is a side elevational view, the opposite side being substantially a mirror image thereof;

FIG. 4 is a cross sectional view taken on line 4—4 in FIG. 3;

FIG. 5 is a cross sectional view taken on line 5—5 in FIG. 3;

FIG. 6 is a cross sectional view taken on line 6—6 in FIG. 3; and

FIG. 7 is a top plan view thereof.

We claim:

The ornamental design for a molded guitar carrying case shell, substantially as shown and described.
